UNITED STATES PATENT OFFICE.

ALDEN A. BARTLETT, OF SAN FRANCISCO, CALIFORNIA.

WOOD-CUTTING MACHINE.

SPECIFICATION forming part of Letters Patent No. 758,042, dated April 26, 1904.

Application filed September 24, 1903. Serial No. 174,530. (No model.)

To all whom it may concern:

Be it known that I, ALDEN A. BARTLETT, a citizen of the United States, residing at San Francisco, in the county of San Francisco and 5 State of California, have invented a new and useful Improved Wood-Cutting Machine, of which the following is a specification.

My invention relates to machines for reducing fern and the like wood to sawdust or pulp; 10 and my object is to provide a machine of this character which will efficiently reduce wood of the character indicated to a state of fine division and such a machine in which the number of parts shall be the fewest possible consistent with the work required of it and which 15 shall be efficient in operation and durable in use.

My invention particularly relates to a machine designed especially to operate upon 20 ferns, such as those that grow in the Hawaiian Islands, the texture of which more nearly resembles wool than wood, and therefore is of such a peculiar nature as to render it difficult if not impracticable of separation into fine particles by the usual wood-cutting means with 25 which I am familiar, because it is found that instead of being severed by the usual cutting knives or devices it yields under the action of the same. This class of woods or plants grows 30 luxuriantly in the Hawaiian Islands to various thicknesses up to four feet in diameter, and it may be briefly described as composed of round or wire-like fibers interwoven in a matted state, as a result of which peculiar texture all attempts to cut it by knives operating 35 either at right angles to the longitudinal axis of the wood or in line therewith are practically ineffective, because the result is simply a tearing of the wood and without an effective 40 division of the same into sawdust or pulp. I have found that this fiber can be properly reduced to the required state of division by a specially-constructed cutting mechanism in 45 which the cutting devices or elements are presented to the material so as to act upon the same in the manner of a screw and are disposed that they are presented to the wood at an angle to the surface of each individual fiber, such angle being substantially at right

angles to the texture of each of said individual fibers and combined with means, manual or mechanical, for feeding the material to the cutting or sawing mechanism. 50

A further object of my invention is to provide means for regulating the distance the cutting edge projects for cutting action on the fiber, which means enable me to compensate for the wear of the cutting-knives. 55

With these objects in view my invention consists in the novel construction and combination of parts, as hereinafter described with reference to the accompanying drawings, and more particularly pointed out in the claims. 60

In the drawings, Figure 1 is a side elevation of the machine embodied in my invention. 65 Fig. 2 is a plan view thereof. Fig. 3 is a cross-section on the line 3 3 of Fig. 2. Fig. 4 is a side view of a section of teeth of the cutters. Fig. 5 is an end view of the same. Fig. 6 is a section showing the means for securing the cutters to the cylinder, and Fig. 7 70 is a view of the cylinder with the cutters removed.

Similar reference characters refer to like parts throughout the several views. 75

The frame 1 has bearings 2 for the reception of the horizontal shaft 10, on which is mounted the cylinder 3, supporting the cutting or sawing device, consisting in this instance of the spiral band-saws 4, as shown, so 80 that they may form a series of spirally-disposed teeth which will act upon the fiber of the wood after the manner of a screw, and thereby assist in drawing the wood through the machine, which feeding action may be supplemented by hand or by any suitable mechanical means. The spiral knives may be long enough to reach from end to end of the cylinder or may be in sections. I prefer to construct the cylinder with end shoulders 20, 85 as shown in Fig. 7, to support the cutters. These cutters may be L-shaped in cross-section and securely held against the cylinder by plates 21 and screws 22. The distance the cutters project beyond plates 21 is regulated 90 by the thickness of the strips 23 of lead, soft iron, wood, or any other desirable material. The teeth of the cutters preferably do not 95

project more than three-fourths of an inch. When worn, the thickness of 23 may be reduced to allow the teeth to project farther.

Suitably secured to the supporting-frame is 5 a feed table or trough 5, terminating in a wedge-shaped box or receptacle 6, extending from the feeding end of the cylinder to the opposite end thereof, said table extending at an angle to the cutting device, so as to direct 10 the wood against the cutting edges thereof diagonally with respect to the length of said wood, as shown in Fig. 2, and extending from the top of said trough is a segmental shield or guard-plate 7, overlapping and inclosing the 15 upper quadrant of the cutting-cylinder opposite to said feed table or trough. Between the lower or bottom portion of the wedge-shaped receptacle or box 5 and the cutting-cylinder is a discharge-opening 8, adapted to direct the 20 finely-divided particles from the machine and preferably onto a suitable conveyer of any convenient form, such as a belt 9, passing around suitable shafts 19, journaled in bearings of the fixed frame below the feeding-trough and operated 25 in any suitable manner from the driving-shaft of the machine—such, for example, as by means of the worm-screw 14 on one end of the shaft 10, meshing with the worm-gear 15 on one end of one of the shafts 19; the 30 main driving of the machine being effected through the medium of a spur-gear or pulley 11, mounted on the shaft 10 and deriving its motion from any suitable spur-gear or belt (not shown) driven from any suitable source 35 of power or by any other equivalent driving means. After the material or divided particles fall upon the conveyer-belt they are conveyed by the same to any convenient point of discharge, and I have indicated conventionally 40 a discharge-chute on the hopper 17, through which the particles are directed to any suitable point or to cars, boxes, or other receptacles placed thereunder.

Having now explained my improvement, what I claim as my invention, and desire to 45 secure by Letters Patent, is—

1. In a machine for reducing wood to saw-dust or pulp, the combination of a rotating cylinder, saw-teeth spirally disposed around the same, said saw-teeth having a base at right angles to the cutting portion whereby said saw-teeth may be secured to said cylinder, of a feed box or table disposed at an angle to said cutting-cylinder terminating in a wedge-shaped box extending substantially the length 55 of and adjacent to the cutting-cylinder and adapted to direct the material against the cutting edges at an angle thereto, substantially as described.

2. In a machine for reducing wood to saw-dust or pulp, the combination of a rotating cylinder having collars at its ends, said collars having projecting shoulders with spiral faces, and saw-teeth spirally disposed around said cylinder abutting against said shoulders 65 and resting against the spiral faces of said shoulders, substantially as described.

3. In a machine for reducing wood to saw-dust or pulp, the combination of a rotating cylinder having collars at its ends, said collars having projecting shoulders with spiral faces, saw-teeth spirally disposed around said cylinder and abutting against said shoulders and resting against the spiral faces of said shoulders, plates and screws to secure said 75 saw-teeth to the cylinder, and spacing-strips to regulate the distance the teeth project beyond the securing-plates, substantially as described.

In testimony whereof I have signed my name 80 to this specification in the presence of two subscribing witnesses.

ALDEN A. BARTLETT.
